WILLIS J. SUTCLIFFE, OF CEDAR HEIGHTS, IOWA

AUTOMATIC TARGET TRAP

Application filed March 2, 1931. Serial No. 519,602.

My invention relates to improvements in automatic target traps, and the object of my improvement is to provide mechanism for such a trap whose interactions therewith are so correlated as to variably change the direction and scope of movement of the target delivery means of the trap as to prevent any predetermination by a marksman as to either.

This object I have accomplished by the means which are hereinafter described and claimed, and which are illustrated in the accompanying drawing, in which Fig. 1 is a top plan of a target trap set for delivery of a target and of my improved operating mechanism as associated therewith. Fig. 2 is a side elevation of said trap only, showing certain connections of said mechanism therewith, other parts removed or broken away. Fig. 3 is a detail side elevation of parts of the cam-controlled connections to an operating rod for said trap.

In target traps now in use, the slinging action of the trap as to scope and change of direction in flinging a target body is such, that in the respective and successive changes a certain regularity exists, whereby an experienced marksman used to such changes can readily predetermine such changes, giving him an advantage over those who are inexperienced in this regard, and thus in any event forestalling a fair and unpredicted scoring in any competition, or even in securing for the marksman himself a real showing and test of his expertness.

My device therefore offers to marksmen a means for absolutely unpredictable tests of marksmanship.

I have shown in Figs. 1 and 2 a well-known target trap, and as associated with my improved operating mechanism, but I do not specifically claim this make of trap which is used herein for exemplification only, as it will be understood that my improved operating mechanism may be associated operatively with other types of traps, with any minor modifications or changes of connections as may be necessary and not departing from my invention herein.

Said trap shown in plan in Fig. 1 and in side elevation in Fig. 2, has a base body 3

fixed on an elongated support 1 at one end of the latter. This base 3 has an erect spindle indicated in dotted lines in Fig. 2 on which is pivotally rockingly mounted a main frame 13 with a slightly inclined integral arm 4 on whose outer extremity is a bearing-arm 5 and 6 carrying a rocking segmental gear 7, and a coiled tension spring 9 is connected to said gear eccentrically, and at its other end to the frame 13. A slinger arm 60 55 8 is rigidly secured at one end to said gear, and carries at its opposite end the usual target carrier 11 having at one side an engaging seat for a discoidal composition target 12, and the carrier has a lateral finger 65 14 notched at one longitudinal edge to seat a detent or catch 15 on a rockable arm depending and medially pivoted in a hollowed seat in said frame, as indicated in dotted lines in Fig. 2 for end connection to linking 70 means 16, being a sprocket-chain around and in mesh with a small sprocket-wheel 66 on a shaft 66' in the bearing 5 on which the segmental gear 7 is fixed to rotate therewith. The gear-teeth on the gear 7 are, however, 75 for a purpose not incidental to this invention.

A lighter coiled tension spring 10 is connected between the arm 8 and one end of the slinger or target-carrier 11 which is pivoted to the arm 8, and tends to keep the finger 14 80 in engagement with the catch-detent 15. The chain 16 is carried through a hollow in the body 13 and has a terminal eye 18 engaged with a loop 17 connected at 19 to a general operating rod 51 of the usual type, leading 85 to an operating lever of a well-known kind not shown. One one side face of the rock-body or frame 13 is fastened a plate 22 having a lateral arm 20 provided with three bolt-holes 21 at varying distances from the frame 90 13. On the elongated base 1 is mounted an operating mechanism for said trap as follows.

The numerals 35 and 54 denote intermeshing gears rotatably mounted on the base 1, 95 the gear 54 being the smaller. Above the level of said gears, and placed intermediately over their meshing teeth is a fixed deflector body 55 having at one end a terminally diminished part 56 with an arcuate outer 100

edge eccentric to the gear circle of the larger gear 35, but overlapping its teeth.

A pawl 52 is yieldably kept in mesh with the teeth of the gear 54 by a spring 53. The gear 35 has thereon an integral eccentric sheave 36 provided with an eccentric strap 38, the latter having an arm 38'. The numeral 39 denotes an elongated U-shaped bar whose terminations are pivoted swingingly upon the axis 37 of the gear 35. At 43 in the lower reach or part of the bar 39 is pivoted a pawl 42 having a flat upturned termination adapted to ride upon the curvate outer edge of the fixed deflector member 56 at times. A spring 44 connected between the pawl at 45 and the outer end of the bar 39 retains the pawl yieldingly upon said deflector, or at other times in engagement with teeth of the gear 35. The detail of an arm made up of parts 46 and 49 is shown in Figs. 1 and 3. One end of the bar part 49 has an eye secured at 50 to the nut connection 19 to the operating rod 51. The opposite end of the part 49 is threaded to seat an adjusting nut 48 which is between downturned apertured parts of the bar part 46, and a coiled spring 48 between said nut and one of said downturned parts at 47 allows some free play of the member 46 on the part 49. The other termination of the part 46 is apertured and pivoted on the pivot-bolt 41 which is passed downwardly through registering longitudinal slots 40 of the U-shaped arm 39 to play to and fro therein. The bolt 41 also traverses the end of the arm 39 of the eccentric strap 38.

The numeral 23 denotes an angle-plate fastened on the nut connection 19 of the operating rod 51, and is apertured to pass a rod 24 to slide loosely, a spring 25 on the rod between a terminal adjusting nut 26 and said angle-plate permitting some play to the rod between the nut 26 and another adjusting nut 27 on the threads of the rod. The other end of said rod is threaded to receive adjustable spaced nuts 28 and 29, and on the intermediate portion of the rod between said nuts an apertured pawl member 32 has free but limited play, the other end of the pawl being pivoted to the base member 2. A swinging tension spring connected between a block 34 on said base and an eye 33 on the pawl is positioned so that it may swing to either side of the pawl pivot to be past a dead center in either of opposite directions, the pawl detent 31 being engageable with teeth of the gear 35.

The numeral 58 denotes a connecting rod pivoted at one end on a crank-pin 59 of the smaller gear 54, the other end part of this rod (see Fig. 2) is passed loosely through apertures in one downturned end of a bar 60 and a downturned end of a bar 62, the other ends of the bars 60 and 62 being separated to provide a fork embracing the lateral pro-

jection 20 of the said side bracket on the trap body 13, the bars 60 and 62 being fastened together, the end of the bar 62 as turned down being apertured and threaded to seat the threaded part of the rod 58. Nuts 63 on the threaded part of the rod with coiled springs 64 and 65 at either side thereof serve to take up for jar on the rod parts. 70

Operation. The trap as shown in said Figs. 1 and 2 is set in a middle position with the target holder 11 in its pre-discharge position, the spring 9 under tension. 75

In order to release the catch 15 the operating rod is shifted a short distance toward the trap, its connection 16 rocking the catch arm (shown in dotted lines in said Fig. 2), and releasing the finger 14, whereupon the recoil of the heavy spring 9 on the segment 7, rotates it swiftly together with the target holder 80 to fling the target 12 outwardly. 85

The return and then repeated forward movement of the operating rod also actuates the gears and other elements of the device concurrently, in causing an indeterminable amount of shifting of the gears, and consequent variation of the direction of the throw of the target, as related to previous and subsequent throws thereof. 90

When the operating rod 51, after release of the catch 15, is pulled back the flanged pawl 42 rides back off from the deflector 56 over the teeth of the gear 35 to a distance determined by the position of the eccentric 36 fixed on and rotating with the gear 35 in varying the throw of the arm 39 of the eccentric strap on the pivot bolt 41 and the arm 46 and 49 and rod 51, the pawl then engaging teeth on the gear 35. The operating rod 51 is then moved forwardly swinging the eccentric-strap arm 42 until the pawl 45 rotates the gear 35 in the direction of the arrow so that the pawl again rides upon the deflector and is lifted out of engagement with the gear. The attendant at the trap has returned the target carrier so that the finger 14 locks with the catch 15, and another target 12 is placed. 100 110

The trap is thus reset for another throw. During the first said reversed movements of the operating rod 51 and on the said return movement of the rod, it will be understood that there is no rotatory movement of the gears. When the gear 35 is partially then rotated on the ensuing forward movement of the rod 51 by the pawl 42, at the end of such forward movement, the block 19 and arm 24 in being also moved forwardly bring the pawl 32 forwardly to engage its detent 31 with teeth of the gear 35, and as the pawl in this position has swung the spring 30 past its dead center, the pawl is locked with said gear. In this partial rotation of the gear 35 the intermeshed smaller gear 54 is rotated in the direction of the arrow thereon, and the connecting rod 58 and 60 rocks the bracket 20 forwardly a distance also determined by the 120 125 130

action of the eccentric 36. The rockable body 13 is thus set at a different angular position relative to its fixed supporting base 3 than on its previous position, as is evident. Then a short further movement of the operating rod 51 repeats the disengaging of the catch 15, releasing the carrier 11 and throwing the target 12 in a different direction from the one previously thrown. As the action of the eccentric 36 on the strap 38 and arm 39 thereof constantly varies the length of throw of the arms 46 and 49, and in variously limiting the rotations of the gears, which is due to the varying movements of the arm 39 as the eccentric 36 changes its position relative thereto, it is obvious that no predetermination is possible of any successive scope of rocking movements of the body 13 of the trap. When in the return pull on the operating rod to reset the pawl 42 the rod 24 moving therewith swings the pawl 32 back, its spring 30 is swung past its dead center in the opposite direction, and the pawl is thus held out of engagement with the gear 35 which may then freely rotate when the next forward swing of the pawl 42 rotates the gears as before stated a relative distance determined by the then varied position of the eccentric.

Having described my invention, what I claim as new, and desire to secure by Letters Patent, is:

1. An apparatus of the character described, comprising a target trap having a movable frame mounted on a relatively fixed base, a releasably locked resiliently controlled target throwing arm mounted swingingly on said frame, and mechanism associated with said trap operable to release the throwing arm while relatively moving said frame, said mechanism including intermeshed gears, an eccentric on one gear, a strap thereon and a pawl operably connected to said strap, said pawl movably mounted to engage and rotate the eccentric-carrying gear partially, a deflector member positioned to lift said pawl out of engagement with said gear at the end of its stroke, operating means for said trap connected to said eccentric strap, and pawl means for releasably engaging the eccentric carrying gear linked movably to said trap operating means for locking said gear at times when the first pawl is idly returning to its engaging relation to the gear, the other gear having a linking connection to said movable frame to move the latter when said throwing member is released.

2. An attachment for a target trap having a rockable frame, a resiliently controlled target throwing arm thereon and a resiliently controlled locking device on the frame to releasably engage said arm, said attachment consisting of meshed gears of different diameters, connecting means eccentrically connected to both said frame and to one of the gears, the other gear having an eccentric fixed there-

on, an eccentric-strap on said eccentric having an arm projection, an operating rod connected to said throwing arm, an adjustable connecting means connected between said operating rod and said eccentric-strap arm, a deflector adjacent the eccentric-carrying gear, a resiliently controlled pawl on said eccentric-strap arm adapted at different times to mesh with said gear or to ride out of mesh upon said deflector, and a resiliently controlled locking pawl adjustably connected to said operating rod to mesh or unmesh with said eccentric-carrying gear at different stages of meshing or unmeshing of said eccentric-strap arm pawl with said gear.

In testimony whereof I affix my signature.

WILLIS J. SUTCLIFFE.
